UNITED STATES PATENT OFFICE.

FRANK LE FEVER, OF FULTON, NEW YORK.

BREECH-LOADING SINGLE-BARREL GUN.

Application filed October 21, 1919, Serial No. 332,249. Renewed September 4, 1923.

To all whom it may concern:

Be it known that I, FRANK LE FEVER, of Fulton, in the county of Oswego, in the State of New York, have invented new and useful Improvements in Breech-Loading Single-Barrel Guns, of which the following, taken in connection with the accompanying drawings, is a full, clear, and exact description.

- 10 This invention relates to certain improvements in breech-loading guns of the single-barrel type commonly known as "trap" guns, in which the barrel and frame are movable one in relation to the other to permit the 15 insertion and ejection of the cartridges and are held in their closed position by a suitable locking bolt.

These guns are generally used by expert marksmen and therefore require the very 20 best materials and most skilled workmanship in their construction, all of which necessarily increases the cost of manufacture and establishes a relatively high retail price, thereby greatly restricting the manufacture 25 and sale.

Furthermore, the complicated mechanisms which usually enter into the construction of guns of this character require that they be handled with the utmost care in order to 30 keep them in perfect working condition and one of the main objects of my present invention is not only to materially reduce the cost of manufacture and retail, but also to produce a more sturdy and dependable gun 35 than has heretofore been practised.

In other words, I have sought to increase the working efficiency and durability and at the same time to simplify the construction and work of assembling, reducing the number of parts, which also materially reduces 40 the weight of the completed gun.

One of the specific objects is to lock the barrel and frame at the breech with a wedging action of the locking bolt so that it 45 may automatically take up the slight wear caused by repeated opening and closing of the gun at said breech.

Another specific object is to provide operating mechanism for the locking bolt with 50 a toggle movement, one of the members of which is spring-pressed longitudinally and has an independent oscillatory movement by which the locking bolt is held in its locking position under spring tension and is also 55 automatically held in its unlocked or tripped position.

Another object is to employ a similar toggle movement in the operation of the hammer.

A further specific object is to permit the 60 cocking of the hammer by means of a sliding pawl on the barrel lug.

A still further object is to control the operation of the ejector in such manner that the cartridge containing the charge will be 65 slightly withdrawn to permit its removal by hand when the gun is broken at the breech, and also to cause the blank cartridge to be wholly ejected from the barrel when the hammer is released for firing said cartridge. 70

Other objects and uses relating to specific parts of the gun will be brought out in the following description.

In the drawings:

Figure 1 is a longitudinal sectional view 75 of a portion of a single-barrel breech-loading trap gun embodying the features of my invention.

Figure 2 is a horizontal sectional view taken approximately in the plane of line 80 2-2, Figure 1, showing more particularly the means for operating the locking bolt.

Figure 3 is a longitudinal sectional view of a portion of the same gun from the opposite side from that shown in Figure 1. 85

Figure 4 is a transverse vertical sectional view taken in the plane of line 4-4, Figure 1.

Figure 5 is an end view of the breech face of the frame partly in section to show the 90 locking bolt and guide therefor, the barrel being omitted.

Figure 6 is a transverse sectional view taken in the plane of line 6-6, Figure 1.

Figure 7 is a side elevation of a portion 95 of the breech end of the barrel showing the adjacent portion of the frame in section together with the locking bolt for holding the frame and barrel in locked position.

Figure 8 is a detail sectional view showing the means for holding the locking bolt in its tripped position. 100

As illustrated, this gun comprises a frame 105 -1- having a trigger plate -2-, a stock -3-, and a barrel -4- having a fore-end piece -5-. The frame -1- is provided with a breech face -6- against which the adjacent end of the barrel is adapted to abut when closed and is also provided with an extension -7- projecting forwardly from the breech face -6-, the main body of the frame being chambered from the bottom 110

upwardly and from the rear end forwardly to receive various operating parts herein-after described, leaving the upper portion and sides integral with the main body while 5 the lower side and rear end are closed by the trigger plate —2— which latter is held in place by screws —8— and constitutes part of the frame.

The frame —1— and stock —3— may be 10 secured together end to end by any suitable fastening means, but preferably by means of a bolt —9— passing through a lengthwise opening —10— in the stock and engaged in a threaded aperture —11— in the rear 15 end of the trigger plate —2— which forms the rear wall of the chamber —1'—.

The barrel —4— is hingedly mounted upon the extension —7— to swing vertically so that when closed its rear end will abut 20 firmly against the breach face —6— of the frame —1— and for this purpose is provided on its under side with a lug —12— movable in an opening —13— in said extension and having its front end face provided with a semi-circular bearing —14— engaged with a pivotal pin —15— which is also mounted upon the extension —7—.

The front end face of this extension is concentric with the pivotal pin —15— and 30 serves as a bearing for the rear end of the fore end piece —5— which is detachably secured to the under side of the barrel in any well-known manner not necessary to herein illustrate or describe except that the 35 mechanism by which it is locked to the barrel must be easily accessible for unlocking to permit the fore-end to be removed when it is desired to detach the barrel from the frame.

40 The rear end of the barrel is provided with a pair of similar lugs —16— disposed in parallel vertical planes at equal distances from opposite sides of the longitudinal center of the gun and extend rearwardly beyond the breech face —6— into corresponding recesses or vertical slots in the frame —1— when the gun is closed for holding the adjacent portions of the frame and barrel against relative lateral movement 45 and at the same time affording means whereby said frame and barrel may be locked in their closed positions.

The rear ends of these lugs are provided with recesses —17— which, when the gun 55 is closed, register with a transverse bolt opening —18— for receiving a locking bolt —19— to hold said frame and barrel in their closed positions, the lower side of the locking bolt being provided with lengthwise 60 inclined faces or cams —20— spaced to correspond to the spacing of the lugs and exerting a wedging pressure against the lower walls of the respective recesses to compensate for wear and to thereby firmly

hold the frame and barrel in their closed 65 positions.

The means for operating the locking bolt —19— comprises a lever —21— pivoted at 70 —22— to the upper portion of the frame —1— to swing laterally across the top of said frame and is provided with an arm —23— secured thereto and engaging the under side of the upper portion of the frame as shown in Figure 1 in such manner 75 as to hold the lever —21— in its operative position and at the same time serving as a part of the means for shifting the locking bolt —19— transversely in its guide opening —18—, said locking bolt and its 80 guide being square in cross-section to hold the bolt against turning.

The forward end of the arm —23— is engaged in a groove or notch —24— in the under side of the locking bolt —19— and its rear end is provided with a lateral projection or flange —25— for cooperative engagement with a plunger —26— which together with said arm constitutes what may be termed a toggle for operating the bolt —19—.

The member —26— extends lengthwise of the gun, the forward end thereof being provided with a relatively small spherical bearing —27— engaging in a corresponding socket —28— in the pendant flange —25— of the arm —23—, the rear end of said plunger being engaged in an aperture —29— in the flange or post as —2'— of the trigger plate —2—. A coil spring —30— encloses the shank of the plunger —26— and has one end engaged with the post —2'— and its other end engaged with a shoulder —31— on the plunger for exerting forward pressure upon the pending flange —25— of the arm —23—.

The guide-opening —18— extends through the lefthand side face of the frame —1—, the opposite end being closed thus permitting the bolt —19— to be moved through said open side when tripped to unlock the gun frame, said bolt being movable in the opposite direction to lock these parts together.

The turning connection between the rear end of the arm —23— and plunger —26— is normally at the left-hand side of a direct line between the axis of the pivot of the lever —21— and rear end bearing —29— of the plunger, so that the forward pressure of the spring upon the plunger may yieldingly hold the bolt —19— in its locked position thereby wedging the cams —20— against their respective lugs —16— to compensate for wear and to thereby assure a firm locking of the connection between the barrel and frame when the gun is closed.

When the locking bolt —19— is withdrawn from its locking position by the

operation of the lever —21— and its arm —23— against the action of the retracting spring —30— and the gun is broken, said bolt and its operating means are temporarily held against returning by means of a trip-pin —a— which is movable in the frame —1— into and out of an aperture in the front end of the arm —23—, as shown, in Fig. 8, and is provided with an offset 5 end —a'— underlying the rear end of the barrel so that when said barrel is closed it will engage the offset end —a'— and thereby withdraw the pin —a— from the arm —23— against the action of a retracting spring —b— to allow the spring —30— to return the bolt —19— to its locking position.

When the locking bolt is withdrawn from its locking position one end thereof, as for 10 example, the right-hand end, is drawn beyond the corresponding lug —16— at which time a slot —32— in the front face of the locking bolt —19— is registered with the recess for the other lug —16— thus permitting both lugs to be rocked upwardly through the top of the frame when the gun is broken, the upper faces of said lugs being normally flush with the top face of the frame when the gun is closed.

25 A firing pin —33— is slidably mounted in a lengthwise opening —34— in the portion of the frame just back of the breech face —6— for firing the cartridge as "c" and is adapted to be forced to its firing position by a suitable hammer —35— which is pivoted at —36— to said frame and is provided with a forwardly projecting extension —37— adapted to be engaged by a cocking member —38— for cocking the hammer after firing when the gun is broken.

30 A detent —39— constituting an integral part of a trigger —40— pivoted at —41— to the trigger plate —2— is adapted to engage a shoulder —42— on the under side of the hammer for holding the latter in its cocked position.

The means for forcing the hammer to its firing position is somewhat similar to that which operates the arm —23— of the locking bolt —19— in that it consists of a longitudinally movable plunger —43— having its front end provided with a spherical bearing face —44— engaging in a socket —45— in the rear face of the hammer —35— just above the horizontal plane of its pivot —36—, said plunger having its rear end engaged in a bearing —46— in the rear portion of the trigger plate —2—.

35 A coiled spring —47— surrounds the shank of the plunger —43— and has one end bearing against a shoulder on the trigger plate and its other end engaged with a shoulder —48— on the plunger so as to exert forward pressure upon the portion of the hammer —35— above its pivot, tending to

force said hammer into engagement with the firing pin —33—.

The upper rear portion of the hammer —35— and the plunger —43— constitutes what may also be termed a toggle for operating the hammer when the latter is released by the tripping of the detent —39— through the medium of the trigger —40—, said detent and trigger being forced to their holding positions by a spring —49—.

40 The cocking member —38— consists of a pawl slideable forwardly and rearwardly in a suitable recess —50— in the lower side of the lug —12— on the barrel —4— so that its rear end underlies the forward end of the hammer extension —37— which extension, when the hammer is moved to its firing position, lies closely adjacent to the upper face of the rear end of the pawl but when cocked and the gun closed is spaced a sufficient distance above said pawl to permit the gun to be broken without in any way interfering with the cocked position of the hammer.

45 In order that the cocking member —38— may be positively held against releasing its engagement with the extension —37— of the hammer during the cocking operation in breaking the gun, its forward end is yieldingly held by the tension of a spring —51— against an abutment —52— on the rear end of the fore-end piece —5—, said spring being interposed between suitable shoulders on the lug —12— and pawl —38—, as shown more clearly in Figure 1.

50 The lower portion of the lug —12— and the pawl —38— substantially fills the open lower side of the chamber —13—, the lower faces thereof being substantially flush with that of the frame —1— and fore-end piece —5— when the gun is closed, the front end of the pawl being movable in an upwardly and rearwardly inclined guide-way —53— formed in the rear wall of the chamber —13— and serving to aid the spring —51— in returning the pawl to its normal position during the closing of the gun.

55 The ejector mechanism comprises a pair of parallel lengthwise rods or bars —55— —55'— movable in corresponding lengthwise openings or ways —56— in the lower portion of the rear end of the barrel —4— and are secured at their forward ends to a head —57— which normally fits in a corresponding recess in the adjacent portion of the barrel and is provided with a shoulder —58— for engaging the end of the cartridge "c" to expel said shell from the barrel as the bars —55— and —55'— are moved rearwardly in a manner presently described.

60 Suitable provision is made for gradually operating the ejector bars to partially withdraw the loaded or unfired cartridge from the barrel, sufficient to permit it to be removed by hand when the gun is broken and

the hammer still in its cocked position, and also for forcibly ejecting the fired cartridge clear from the barrel when the gun is broken with the hammer in its fired position.

- 5 For these purposes is provided a longitudinally movable driving member —60—, slidably mounted upon a rod —61— which, in turn, is secured to a rocking member —62— so that the rod —61— with the driving member —60— thereon may move about the pivotal axis of the rocking member —62—, said driving member being provided with a shoulder —63— for engaging the rear end of the fore-end piece —5— under the pressure of a spring —64—.

The rear end of the driving member —60— constitutes an abutment normally aligned with and in close proximity to the front end of the ejector bar —55— while the rear end of the rod —61— travels in close proximity to the curved front end of the frame extension —7— as the gun is opened and closed, the rocking member —62— being pivoted at —62'— to the metal shank of the fore-end piece —5— and together with the rod —61— and driving member —60— are removable with said fore-end piece.

80 The spring —64— surrounds the adjacent portion of the bar —61— and abuts at its ends against the member —62— and driving member —60— respectively, thereby normally exerting rearward pressure upon the driving member —60— while the rear end of said driving member is spring-pressed against the forward end of the ejector rod —55—.

The head —57— of the ejector rod rides against the breech face —6— of the frame 40 when the gun is closed, thereby forcing said ejector rod rearwardly against the rear end of the driving member —60— against the action of the retracting spring —64— thereby normally holding the shoulder —63— a short distance away from its companion shoulder —63'— on the fore-end piece.

It therefore follows that when the gun is broken, thereby withdrawing the breech face 50 of the barrel from the breech face of the frame, the spring actuated driving member —60— will exert a rearward driving force upon the ejector bar —55— and the cartridge engaged thereby until the shoulder —63— engages the shoulder —63'— at which time the cartridge will have been withdrawn from the barrel a sufficient distance to permit it to be engaged and removed by hand, it being understood that when the gun is closed the head of the ejector bar will 60 ride against the breech face —6—, thereby forcing said bar forwardly and returning the driving member —60— to its normal position against the action of the spring —64—.

65 This driving member —60— is also em-

ployed to forcibly eject the cartridge blank after the same has been fired by the action of the hammer —35—, and to this end I have provided another sliding bar or rod —65— which is movable longitudinally in a guideway —66— in the extension —7— of the frame —1— and has its rear end provided with a recess —67— for receiving a pin or lug —68— on the hammer —35— or its pin —36—, the ends of said recess constituting 70 shoulders by which the rod is driven forwardly or returned as the hammer is released or cocked, the front end of the rod —65— being normally coincident with, or slightly at the rear of the curved front face 75 of the extension —7— where it is out of the path of movement of the rear end of the rod —61— when the gun is broken or taken apart and the hammer in its cocked position.

Now, if the hammer is released and forced 80 to its firing position, the rod —65— will be driven forwardly to cause its front end to protrude slightly beyond the curved front face of the extension —7— and into the path 85 of movement of the rear end of the rod —61—, said forward end of the rod —65— being disposed near the lower side of the frame of the gun some distance from the rod —61— when the gun is closed, so that 90 when it is opened the rod —61— will be carried down across the curved front face of the extension —7— until the cartridge in the breech of the barrel is clear from the top of the frame and at about this time the rear end of the rod —61— will have engaged the 95 forwardly protruding end of the rod —65— which engagement will then trip the driving member —60— from holding engagement 100 with the shoulder —63— and allow the spring —64— to instantly drive the member —60— and ejector rod —55— rearwardly to 105 eject the cartridge blank with sufficient force to remove it entirely from the barrel.

The gun is then closed with or without 110 a loaded cartridge therein, thereby causing the head —57— to ride against the breech face —6— by which operation the ejector bar and driving member —60— will be restored to their normal positions against the action 115 of the spring —64—, it being understood that the point of engagement of the member —60— is in a plane below the pivot —62'— which causes the shoulder —63— to assume a position ready for engagement with the shoulder —63'— when the gun is broken with the hammer cocked.

What I claim is:

1. The combination with the frame and barrel of a breech-loading gun, of means for locking and releasing the barrel and frame in and from their closed positions, said means comprising a locking bolt slideable transversely of and upon the frame, a lever pivoted to the frame and having one end 125 engaged with the bolt for shifting the same,

a plunger extending lengthwise of the gun and having one end bearing upon the frame and its opposite end spring-pressed into engagement with said lever, to force the bolt 5 to its locking position, and means controlled by the opening of the gun for holding the locking bolt from its locking position.

2. In a single-barrel breech-loading gun, a pair of lugs on the breech end of the barrel 10 at opposite sides of the axis thereof and movable into and out of recesses in the breech face of the frame and having their upper edges disposed in a plane between the upper face of the barrel and said axis to 15 form abutments, a locking bolt movable transversely of and within the frame across both of the recesses in the breech face thereof and provided with a pair of cam faces on its lower side spaced a distance apart 20 corresponding to the spacing of said lugs and recesses and movable into and out of engagement with the abutments on the upper edges of said lugs for tightening and releasing the barrel in and from its closed position, said 25 locking bolt having one end movable into and out of registration with one of the lugs and provided with an upright slot movable into and out of registration with the other lug for locking and releasing the barrel in and from its closed position and means 30 for operating the locking bolt.

3. In a single-barrel breech-loading gun, a pair of lugs on the breech end of the barrel 35 at opposite sides of the axis thereof and movable into and out of recesses in the breech face of the frame and having their

upper edges disposed in a plane between the upper face of the barrel and said axis to form abutments, a locking bolt movable transversely of and within the frame across 40 both of the recesses in the breech face thereof and provided with a pair of cam faces on its lower side spaced a distance apart corresponding to the spacing of said lugs and recesses and movable into and out of 45 engagement with the abutments on the upper edges of said lugs for tightening and releasing the barrel in and from its closed position, said locking bolt having one end movable into and out of registration with one of the lugs and provided with an upright slot movable into and out of registration with the other lug for locking and releasing the barrel in and from its closed 50 position, a hand lever pivoted on the frame and provided with a forwardly projecting extension engaging in a recess in the under side of the locking bolt for shifting said locking bolt in reverse directions, and means for locking the bolt in its unlocked position and having a portion thereof spring 55 pressed into the path of movement of the barrel to be engaged thereby when the barrel is closed for withdrawing said means from its bolt holding position.

In witness whereof I have hereunto set my hand this 7th day of October, 1919.

FRANK LE FEVER.
